(57) **CLAIM**

The ornamental design for an end mill, as shown and described.

DESCRIPTION

FIG. 1 is a front view of an end mill showing my new design; FIG. 2 is a rear view thereof;

FIG. 3 is a top plan view thereof;

FIG. 4 is a bottom plan view thereof;

FIG. 5 is a right side view thereof; and,

FIG. 6 is a left side view thereof.

The broken lines in the drawings illustrate portions of the end mill that form no part of the claimed design.
